(57) **CLAIM**

The ornamental design for a wall-mounted boxing speed ball, as shown and described.

DESCRIPTION

FIG. 1 is a rear, top and left side perspective view of a wall-mounted boxing speed ball, showing my new design; FIG. 2 is a front, bottom and right side perspective view thereof;

FIG. 3 is a front view thereof;

FIG. 4 is a rear view thereof;

FIG. 5 is a right side view thereof;

FIG. 6 is a left side view thereof;

FIG. 7 is a bottom plan view thereof;

FIG. 8 is a top plan view thereof.

FIG. 9 is an enlarged view of portion 9 shown in FIG. 1; and, FIG. 10 is an enlarged view of portion 10 shown in FIG. 2. The dot-dash broken lines depict the boundaries of the enlargements that form no part of the claimed design.
